Primary Examiner — Abraham Bahta

(74) Attorney, Agent, or Firm — Boyle Fredrickson, S.C.

(57) **CLAIM**

The ornamental design for an integral child seat, as shown and described.

DESCRIPTION

FIG. 1 is an isometric view of an integral child seat in accordance with the present invention;

FIG. 2 is a front elevational view of the integral child seat of FIG. 1;

FIG. 3 is a rear elevational view of the integral child seat of FIG. 1;

FIG. 4 is a side elevational view of a first side of the integral child seat of FIG. 1;

FIG. 5 is a side elevational view of a second side of the integral child seat of FIG. 1;

FIG. 6 is a top plan view of the integral child seat of FIG. 1; and,

FIG. 7 is a bottom plan view of the integral child seat of FIG. 1.

1 Claim, 7 Drawing Sheets
